LOCOMOTIVE STOKER

Eugene Martin, Erie, Pa., assignor to The Standard Stoker Company, Incorporated, a corporation of Delaware

Application May 28, 1937, Serial No. 145,197

6 Claims. (Cl. 198—15)

This invention relates to locomotive stokers and particularly to the conveying system thereof.

The principal object of this invention is to provide, in a locomotive stoker employing a pair of conveyors provided with an offset between their adjacent ends, a novel driving arrangement which permits operation of such conveyors from their adjacent ends in a manner whereby one conveyor may deliver in an endwise direction to the offset conveyor, the construction affording direct conveyance of fuel and with the use of but few parts.

It is also an object of this invention to provide, in a locomotive stoker employing several conveyors provided with an offset between their adjacent ends, a novel joint structure which is disposed exterior of the passage for fuel.

More specifically, it is an object of this invention to so arrange this novel joint structure that its assembly and disassembly is facilitated.

Another object of this invention resides in providing a novel drive arrangement for operating the offset conveyors from their adjacent ends by means including a chain which encompasses the axes of the offset conveyors.

Other objects as well as the advantages thereof will become apparent as the following specification is read in connection with the accompanying drawings, in which

Fig. 1 is a vertical section through adjacent portions of a locomotive and tender showing a stoker in which the invention has been embodied, parts being shown in central vertical section and other parts in side elevation;

Fig. 2 and 3 are sectional views taken on the lines 2—2 and 3—3, respectively, of Fig. 1 with portions broken away; and

Fig. 4 is a sectional view taken on the line 4—4 of Fig. 1.

Referring to these drawings, L indicates a locomotive having a firebox backhead 10, a deck 11 and a cab 12. The tender is indicated by T and consists of a frame 13 above which is mounted a tank 14 having the water compartment 15 and the fuel bin 16 disposed above the floor 17 thereof. The stoker for transferring fuel from the tender to the locomotive is generally indicated by S and includes a fuel delivery conduit 18 rigidly secured to the firebox backhead 10 by means of support brackets 19 and 20. On the tender, the stoker consists of a trough conduit 21, the rear portion 22 of which extends into the water compartment 15 while its forward portion 23 extends into an alcove 24 formed at the front end of the tender between the frame 13 and the

floor 17. A vertical plate 25 defines the rearward extent of the alcove 24. Between the locomotive and tender is an intermediate conduit 26, consisting of a front section 27 and a rear section 28 telescoped into said front section. The front section 27 is universally connected at 29 to the lower end of the fuel delivery conduit 18 while the rear section is universally connected at 30 beneath the trough conduit 21.

A conveyor screw 31 is rotatably mounted with 10 in the trough conduit 21 and urges fuel forwardly to the lower rearward end of a conveyor screw 32 disposed within the intermediate conduit 26 which is arranged to conveyed the fuel to the delivery conduit 18. The rearward end of the conveyor screw 32 is offset below the forward end of the conveyor screw 31. A novel means for driving the conveyor screws from their adjacent ends has been provided, and this, together with the improved flexible support for the rearward end 15 of the intermediate conduit 26, will now be described in detail.

The forward portion 23 of the trough conduit 21 comprises a housing 33 secured within the alcove 24 to the frame 13. This housing has an upper cylindrical portion 34 and a subjacent casing 35 which serves to maintain in operative relation the drive shaft 36 of the conveyor screw 32. Bolts 30 secure the cylindrical portion 34 to the rearward portion 22 of the trough conduit 21. A sleeve 37 is rotatably mounted in the cylindrical portion 34 and embraces the conveyor screw 31 passing therethrough. Along its internal portion, the sleeve 37 is provided with a plurality of lugs 38 spaced in a helical relation 30 and arranged to engage corresponding recesses 39 formed in the periphery of that portion of the conveyor screw 31 which is disposed within the sleeve 37. On its outer periphery, the sleeve 37 is provided with gear teeth 40 adapted to be engaged by an endless chain 41 for effecting rotation of the conveyor screw 32.

The sleeve 37 extends forwardly beyond the front surface 42 of the housing 33 and is received in a counter-bored portion 43 of a terminal member 44 secured against the front surface 42 by bolts 45. On its forward end 46, the terminal member is in the form of a spout arranged to discharge fuel into the intermediate conduit 26 for conveyance by the screw 32. Beneath the terminal member 44, the housing 33 is closed by cover 47 which is secured against the front surface 42 by bolts 48. This cover 47 has formed therewith a bearing 49 for the shaft 36 and also a hollow shell 50 having a spherical outer surface 55

- 51 which forms one element of the universal connection 30 between the intermediate conduit 26 and the tender. The shaft 36 has secured thereto a sprocket 52 which is also engaged by the endless chain 41. Motion is transmitted to the chain 41 by a drive unit 53 which includes a casing 54 secured to a side wall 55 of the housing member 33. The casing contains a pair of shafts 56, 57 connected by the gear 58 and pinion 59, respectively. Power, supplied to the shaft 57 from any suitable source by means of a joint 60 (Fig. 2) is transmitted through gearing 58, 59 to the shaft 56 which has secured on an exterior end thereof a sprocket gear 61 engaging the chain 41.
- 15 The forward end of the shaft 36 carries a detachable coupling 62 which is connected in well known manner to a coupling 63, forming a universal joint 64 disposed within the hollow shell 50. On the rearward lower end of the rear conduit section 28 is a semi-spherical flange 28a fitted against the under side of spherical surface 51. In vertical transverse cross section, the rearward portion of the conduit section 28 is substantially U-shaped, the sides 65, 66 of which extend upwardly to embrace the spout 46. A clamp 67 immediately beneath the spout 46 is secured to the sides 65, 66 of the conduit section 28 and cooperates with the spherical surface 51 to form the universal joint 30.
- 30 The clamp 67 has a forward extension 68 which forms with the conduit section 28 a cylindrical portion 69 therein. In this cylindrical portion 69 is mounted a disc 70, the outer surface of which is arcuate to permit angular movement of the disc. The rearward portion of the disc 70 detachably carries the joint coupling 63 and on its opposite side is arranged to receive a disc 71 formed integrally with the conveyor screw 32. Cap screws 72 secure the discs 70, 71 in operative relation. The upper edges of the sides 65, 66 slope forwardly toward the tubular portion of the rear conduit section 28 and detachably support a cover plate 9.
- 45 In the operation of this device, fuel in the bin 16 falls through an aperture 73 of the tender floor 17 into the trough conduit 21. The conveyor screw 31 urges the fuel forwardly past the crusher 14, a portion 75 of which may be secured to the floor 17. At its rearward end, the conveyor screw 31 is provided with a journal 76 received in a bearing 77 of a construction which restrains relative fore or aft movement of the screw incident to its rotation.
- 55 Upon being crushed, the fuel passes into the forward portion 23 of the trough conduit. In order to permit unobstructed passage of fuel through the sleeve 37, that portion of the conveyor screw 31 therein is provided with a hub 78 of reduced diameter. From the cylindrical sleeve 31, the fuel enters the spout 46 and discharges into the lower end of the intermediate conduit 26 for conveyance to the locomotive by the conveyor screw 32.
- 65 Those familiar with the art will recognize that the particular drive arrangement for the conveyor screws 31, 32 permits endwise delivery of fuel by the conveyor screw 31 through the spout 46 and onto the conveyor screw 32. It will also be apparent that the construction permits forward inclination of the intermediate conduit 26 and the screw 32, thereby securing a more direct conveyance of fuel with fewer parts. Since the disc 70 has an arcuate outer periphery, the conveyor screw 32 is thus provided with a suitable bearing which allows for slight angular move-

ment of the screw 32; at the same time, the disc 70 excludes fuel from working around the universal joint 64.

I claim:

1. In a locomotive having a firebox and a tender provided with a fuel bin, a stoker for transferring fuel from said bin to said firebox including a conduit mounted on the tender and arranged to receive fuel from said bin, a conveyor screw in said conduit for urging fuel forwardly, said conduit including a forwardly opening end portion through which fuel is discharged in an endwise direction by said conveyor screw, a conduit extending between the locomotive and tender and at its remote ends being flexibly related with a respective vehicle, the rearward end of the second named conduit arranged to receive fuel from the end portion of the first named conduit, a conveyor screw in the second named conduit having its rearward end offset from the forward end of the first named conveyor screw, and means rearward of the second named conveyor screw for driving the first named conveyor screw from its forward end and the second named conveyor screw from its rearward end, said last named means including a flexible joint on the tender disposed outside the passage for fuel and arranged with its axis of articulation in approximate coincidence with the axis of articulation of the second named conduit.

2. In a locomotive having a firebox and a tender provided with a fuel bin, a stoker for transferring fuel from said bin to said firebox including a conduit mounted on the tender and arranged to receive fuel from said bin, a conveyor screw in said conduit for urging fuel forwardly, said conduit including a forwardly opening end portion through which fuel is discharged in an endwise direction by said conveyor screw, a conduit extending between the locomotive and tender and at its remote ends being flexibly related with a respective vehicle, the rearward end of the second named conduit arranged to receive fuel from the end portion of the first named conduit, a conveyor screw in the second named conduit having its rearward end offset from the forward end of the first named conveyor screw, and means rearward of the second named conveyor screw for driving the first named conveyor screw from its forward end and the second named conveyor screw from its rearward end, said means including a member embracing the first named conveyor screw and being operatively connected thereto, and means operatively connecting said member and the second named conveyor screw, said last named means including a flexible joint on the tender disposed outside the passage for fuel and arranged with its axis of articulation in approximate coincidence with the axis of articulation of the second named conduit.

3. In a locomotive having a firebox and a tender provided with a fuel bin, a stoker for transferring fuel from said bin to said firebox including a conduit mounted on the tender and arranged to receive fuel from said bin, a conveyor screw in said conduit for urging fuel forwardly, said conduit including a forwardly opening end portion through which fuel is discharged in an endwise direction by said conveyor screw, a conduit extending between the locomotive and tender and at its remote ends being flexibly related with a respective vehicle, the rearward end of the second named conduit arranged to receive fuel from the end portion of the first named conduit, a conveyor screw in the second named

named conduit having its rearward end offset from the forward end of the first named conveyor screw, and means rearward of the second named conveyer screw for driving the first named conveyor screw from its forward end and the second named conveyor screw from its rearward end, the rearward end of the second named conveyor screw having a flexible journal within the second named conduit and a flexible driving 10 connection rearward of said flexible journal operatively connecting said screw with said means, said flexible driving connection being arranged with its axis of articulation in approximate coincidence with the axis of articulation of the 15 second named conduit.

4. In a locomotive having a firebox and a tender having a fuel bin, a stoker for transferring fuel from said bin to said firebox including a conduit extending between the locomotive and 20 tender, a conveyor screw within said conduit, a conduit on the locomotive flexibly connected to the forward end of the first named conduit, the rearward end of the first named conduit being in the form of a spherical shell, means on the 25 tender affording a support for the rearward end of the first named conduit, said means comprising a hollow shell having a spherical surface cooperating with the spherical shell of the first named conduit to form a universal joint, a shaft carried 30 by said hollow shell, a disc carried by the rearward end of the conveyor screw, said disc having an arcuate outer surface forming a flexible journal for said conveyor screw in said first named conduit, and a universal joint connecting said disc and said shaft within said hollow shell.

5. In a locomotive having a firebox and a tender having a fuel bin, a stoker for transferring fuel from said bin to said firebox including a conduit extending between the locomotive and 35

tender, a conveyor screw within said conduit, a conduit on the locomotive flexibly connected to the forward end of the first named conduit, the rearward end of the first named conduit being in the form of a spherical shell, means on the 5 tender affording a support for the rearward end of the first named conduit, said means comprising a hollow shell having a spherical surface cooperating with the spherical shell of the first named conduit to form a universal joint, a shaft 10 carried by said hollow shell, a disc carried by the rearward end of the conveyor screw, said disc having an arcuate outer surface forming a flexible journal for said conveyor screw in said first named conduit, and a universal joint connecting 15 said disc and said shaft within said hollow shell.

6. In a locomotive having a firebox and a tender having a fuel bin, a stoker for transferring fuel from said bin to said firebox including a conduit extending between the locomotive and tender, a conveyor screw within said conduit, a conduit on the locomotive flexibly connected to the forward end of the first named conduit, the rearward end of the first named conduit being in the form of a spherical shell, means on the 20 tender affording a support for the rearward end of the first named conduit, said means comprising a hollow shell having a spherical surface cooperating with the spherical shell of the first named conduit to form a universal joint, a shaft carried 25 by said hollow shell, a disc detachably carried by the rearward end of the conveyor screw, said disc having an arcuate outer surface forming a flexible journal for said conveyor screw in said first named conduit, and a universal 30 joint connecting said disc and said shaft within said hollow shell.

EUGENE MARTIN.
